HARMONICA

Egiziano Carloni, Stradella, Italy

Application February 23, 1954, Serial No. 29,146

Term of patent 14 years

(Cl. D56—1)

FIG. 1

FIG. 3

FIG. 2

Figure 1 is a perspective view of a harmonica showing my new design;

Figure 2 is a side elevational view thereof; and

Figure 3 is a cross-sectional view thereof, the upper portion being removed from the base.

I claim:

The ornamental design for a harmonica, as shown.
